UNITED STATES PATENT OFFICE.

EMMA JANE HANEY, OF SENECA FALLS, NEW YORK.

DESIGN FOR A CAT STATUETTE.

47,951.

Specification for Design.

Patented Oct. 12, 1915.

Application filed November 12, 1914. Serial No. 871,800. Term of patent 7 years.

To all whom it may concern:

Be it known that I, EMMA JANE HANEY, a citizen of the United States, residing at Seneca Falls, in the county of Seneca and State of New York, have invented a new, original, and ornamental design for a Cat Statuette, of which the following is a specification, reference being had to the accompanying drawing, forming part thereof.

The figure is a perspective view of a cat statuette, showing my new design.

I claim:

The ornamental design for a cat statuette, as shown.

EMMA JANE HANEY.
